CLAIM

The ornamental design for an oscillating tool, as shown and described.

DESCRIPTION

FIG. 1 is a front perspective view of an oscillating tool showing our new design;

FIG. 2 is a top plan view thereof;

FIG. 3 is a right side view thereof;

FIG. 4 is a bottom plan view thereof

FIG. 5 is a front view thereof;

FIG. 6 is a rear view thereof; and,

FIG. 7 is a left side view thereof.

The broken lines and areas within depict portions of the oscillating tool that form no part of the claimed design.
